FIG. 1 is an exemplary perspective view of a smoke detector chamber, according to an embodiment;

FIG. 2 is an exemplary top plan view thereof, according to an embodiment;

FIG. 3 is an exemplary bottom plan view thereof, according to an embodiment;

FIG. 4 is an exemplary side view of a smoke detector chamber, according to an embodiment;

FIG. 5 is an exemplary alternate isometric view of a smoke detector chamber, according to an embodiment;

FIG. 6 is an exemplary alternate side view of a smoke detector chamber, according to an embodiment;

FIG. 7 is an exemplary alternate perspective view of a smoke detector chamber, according to an embodiment; and, FIG. 8 is an exemplary alternate perspective view of a smoke detector chamber, according to an embodiment.

In the drawings, the broken lines depict portions of the smoke detector chamber which form no part of the claimed design.
